CLOTHES WRINGER CONTROL MECHANISM
OF THE INSTINCTIVE RELEASE TYPESamuel I. Gabrielson, Southport, Conn., assignor
to General Electric Company, a corporation of
New York

Application December 24, 1948, Serial No. 77,213

5 Claims. (Cl. 68—269)

1

This invention relates to power driven wringers, more particularly to power driven wringers of the instinctive type in which a tug on the clothes automatically discontinues wringer operation, such as might occur during an emergency, and it has for its object the provision of a simple, power driven wringer of this type.

More particularly, this invention contemplates an improved power driven wringer having a wringer frame which supports the rolls and which will move in response to a predetermined tug on the clothes, and means operated in response to the movement of the wringer frame for discontinuing the power drive for the wringer rolls.

In accordance with this invention the wringer frame which supports the rolls is mounted for movement with respect to the driving mechanism for the rolls; the movement of the frame is resisted by means which apply to the frame a yielding force and which "give" upon the application of a force of predetermined high value so as to allow the frame to move. This movement of the frame operates a control element of the driving mechanism to cause the power to the rolls to discontinue.

For a more complete understanding of my invention, reference should be had to the accompanying drawing in which Fig. 1 is a front elevation of a wringer embodying my invention, parts being shown in section and other parts broken away so as to illustrate certain details of construction; Fig. 2 is an elevation of certain elements of the control mechanism embodied in the wringer of Fig. 1 and arranged in accordance with this invention; and Fig. 3 is a view similar to Fig. 2 but illustrating the elements in a different operative position.

Referring to the drawing, this invention has been shown in one form as applied to a power driven wringer comprising upper and lower wringer rolls 1 and 2. These rolls are supported in parallel relation and horizontal position by shafts 4 and 5 which are journaled in bearings provided for them in the frame 3. The lower wringer roll 2 is power driven, while the upper roll 1 is frictionally driven from the lower one. The frame 3 is supported by means of a wringer head 6. Frame 3 is mounted on the head 6 so that it may be rotated both forwardly and backwardly with respect to the head; and for this purpose the frame at one end, its lefthand end in Fig. 1, is provided with a pair of vertically spaced outwardly extended ears 7 and 8 which are secured to the head 6 by means of screw

5 studs 9 and 10 directed through coaxial apertures 11 and 12 positioned in a vertical axis and provided in the ears for the studs so as to journal the frame 3 to the righthand side of the head 6, as shown. The frame 3 normally does not move with respect to the head 6, but is held in fixed relation with respect to the head by means of a pair of compression springs 13 (only one shown) mounted between the head 6 and the frame 3 on opposite sides of the vertical axis through the studs 9 and 10. Upon the application of a predetermined force upon the frame, however, the springs 13 will yield in order to permit the frame 3 to move with respect to the head 6.

The left-hand end (Fig. 1) of the lower wringer roll shaft 5 is connected by tubular coupling 14 to a crown gear 15 journalled to a bearing 16 in the head 6. The shaft 5 is provided with opposite parallel flattened sides 5—a which are received in a complementary opening in the coupling. The crown gear is provided with similar flattened sides 16—a which are received in a complementary section of the coupling. The dimensions of the flattened sides 5—a and 16—a and of the complementary parts of the coupling associated with them are such that they permit the aforementioned relative movement between the frame 3 and the head 6 while maintaining the driving connection between the crown gear and the lower wringer roll 2.

The crown gear 15 is selectively driven in opposite directions by pinions 17 and 18 constantly meshing with the crown gear and loose on a vertical shaft 19. This shaft is journalled at its upper end in a bearing 20 in the top wall of the wringer head and has a coupling member 21 in its lower end guided in a tubular post 22 by means of which the wringer head is rotatably supported in the upper end of the wringer post (not shown) of a domestic washing machine. It will be understood that the wringer head is held in fixed angular relation with the wringer post (not shown) by means of suitable releasable detent mechanism (not shown in detail, but which includes a detent 23 controlled by a lever 24). The coupling 21 is provided with a slot 25 by means of which the shaft 19 is driven by a driving shaft (not shown) extending up through the wringer post and driven by any suitable means such as an electric motor (not shown).

The direction of rotation of the crown gear 15, and therefore, the direction of rotation of the wringer rolls, is controlled by coupling one

or the other of the pinions 17 and 18 to the shaft 19. This is effected by means of a shifting member 26 guided to move in a vertical direction in the wringer head 6 and having yokes 27 and 28 received in annular grooves 29 and 30 respectively in gears 17 and 18. Shifting means 26 slides vertically within the wringer head and is operated by means of a shaft 31 journalled in a bearing 32 in the wringer head in its side opposite the wringer rolls and on an axis coaxial with the axis of rotation of the crown gear 15 and the lower wringer roll 2. This shaft 31 is operated manually by handle 33 fixed to its outer end on the outside of the wringer head 6 as shown. On its inner end the shaft 31 carries an inwardly projected cylindrical pin 34 eccentrically related to the axis of rotation of shaft 31 and received in a close fitting circular hole provided for it in the shifting member 26. Thus, when the handle 33 is rotated, the eccentric pin will shift the member 26 vertically. The handle is in a neutral position corresponding to an inoperative condition of the wringer rolls when it is straight down as shown in Fig. 1, and in solid lines in Fig. 2, and in this position the clutch teeth 35 and 36 of the two pinions 17 and 18 are clear of their respective driving pins 37 and 38 fixed on the shaft 19. By moving handle 33 in opposite directions through an angle of about 30 degrees from the neutral position, the handle will swing the eccentric pin 34 to shift the shifting member 26 up and down to effect a driving connection between clutch teeth 36 and its pins 38, or clutch teeth 35 and its pins 37 to drive the crown gear 15 and hence the wringer roll 2 in one direction or the other.

The elements just described are so arranged that if the handle 33 is moved to the right to the dot-dash line position shown in Fig. 2, the roll 2 will operate in a counterclockwise direction as viewed from the right of Fig. 1; whereas if it be moved from the neutral to the full line position of Fig. 3, it will operate the roll 2 clockwise viewed from the same position.

Preferably the shaft 31 is provided with a pair of index balls 39 which are selectively received in any one of three pairs of complementary index sockets 40 located so as to hold resiliently the handle 33 in each of its three operative positions; only the center sockets 40 corresponding to the neutral position are shown.

The means arranged in accordance with this invention for shifting automatically the handle 33 to its neutral position from either driving position thereby to discontinue the driving connection from the shaft 19 to the lower wringer roll 2 comprises a cam 41 in the form of a cylindrical pin fixed to the frame 3 through the medium of a cover plate 42 fixed to the frame 3 and which locates the cam pin above the handle 33, as shown; that is, at a position on the opposite side of the vertical axes through the studs 9 and 10 from the wringer rolls; a cam plate 43 pivoted to the wringer head 6 by means of a pin 44 located below the path of movement of cam 41 in parallel relation to shaft 31 and in the vertical plane containing this shaft, and the plate 43 having upright lateral abutments 45 and 46, inclined away from each other as shown and further, a cam structure 47 in which symmetrical branch slots extend arcuately in opposite directions from a central notch 47a, each said branch having a rise or lobe, respectively 47b, 47c, intermediate its ends; a driving link 48 secured to the handle 33 and shaft to rotate with them and arranged at

right angles to the handle; a pair of drag links 49 and 50 pivotally connecting the ends of the drive link 48 with the ends of the cam plate as shown; and a toggle comprising a toggle spring 51 having its lower end anchored to a pin 52 fixed to the wringer head and its upper end anchored to trolley 53 which has a pin 54 sliding in the curved cam slot. Spring 51 forces pin 54 to ride on the lower surface of the cam slot.

The horizontal distances from the vertical plane passing through the axes of shaft 31 and pin 44 to the pivotal connection points between the drag links 49 and 50 and the cam plate 43 and the pivotal connection points between these links and the drive link 48 are equal, and the drag links 49 and 50 are of equal length; and therefore, the cam plate, drive link and drag links form a parallelogram which causes the cam plate 43 always to assume the same angle as does the drive link 48. Moreover, the parts are so arranged that when the handle 33 is in its neutral position the toggle pin 54 is located in the notch 47a of the cam 47 and is yieldingly held therein by the spring 51, and this toggle arrangement assisted by the index balls 39 yieldingly holds the handle in that position; however, as the handle is shifted in either direction toward either of its running control positions, the cam plate 43 follows the handle movement, and as a result, the pin 54 moves out of notch 47a, rides over a dead center position created by one of the lobes 47b or 47c of the respective cam branch along which the pin happens to be moving and therefore assists in moving the handle to its operative position with a slight "snap" action and holds it there—also again assisted by the index balls 39. Fig. 3 shows the cam and toggle mechanism in a driving position.

Furthermore, the parts are so arranged that when the cam plate 43 is in either driving position of the handle 33, the cam pin 41 lies against one or the other of the inclined walls 45, 46 as shown in Figs. 2 and 3.

Should the wringer be in operation as the result of movement of the handle 33 to its dot-dash position of Fig. 2, and the clothes being fed through the wringer be pulled outwardly by a force great enough to move the wringer frame 3 on its studs 9 and 10 against the force of springs 13, then the frame will pivot counterclockwise looking down upon it, and hence, move the cam pin 41 to the right as viewed in Fig. 2; the pin so moved will operate against the inclined wall 46 and shift the cam plate clockwise. As the plate moves in this way the toggle pin 54 moves back toward the notch 47a and eventually moves over the dead center position in the reverse direction and drops into said notch, thereby automatically returning the handle 33 to the neutral position. Conversely, should the wringer rolls be operated in the reverse direction as a result of movement of the control handle 33 to its position shown in Fig. 3 and the clothes be moved through the rolls in the opposite direction, then if they are pulled out by a force great enough to pivot the frame 3 it will move clockwise looking down upon it and hence move the cam pin 41 to the left as viewed in Fig. 3. And as before, this movement of the pin will pivot the cam plate 43 automatically to return the control handle 33 to its neutral position where it is held by the toggle spring 51.

While I have shown and described a particular embodiment of my invention, it will occur to those skilled in the art that various changes and modifications may be made without departing from

my invention, and I therefore aim in the appended claims to cover all such changes and modifications as fall within the true spirit and scope of my invention.

What I claim as new and desire to secure by Letters Patent of the United States is:

1. In a wringer, a frame, wringer rolls mounted within said frame, driving mechanism for said rolls, a control handle for effecting operation of the driving mechanism to rotate said rolls by movement of the handle from a neutral to a controlling position, means pivotally supporting said frame for rotation with respect to said driving mechanism and control handle, yielding means normally holding said frame in a normally operative position, a toggle spring element, connection means interconnecting said spring element with said control handle to form a toggle between them which holds said handle either in said neutral or in said controlling position depending upon the position of said handle, and shiftable through a dead center position as said handle is moved in either direction between said neutral and controlling positions, and a member movable by said frame as it rotates from said normal operative position against the force of said yielding means for operating said toggle through dead center position to return said handle from said controlling to said neutral position.

2. A clothes wringer comprising wringer rolls, a frame rotatably supporting said rolls, driving mechanism for driving said rolls including a pivoted control handle associated with said mechanism so that when said handle is in a neutral position said mechanism is inactive to drive said rolls and when rotated to two controlling positions on opposite sides of said neutral position controls said mechanism to drive said rolls in forward and reverse directions depending upon the position to which it is moved, a pivoted cam plate adjacent said handle, links interconnecting said cam plate and handle to form a link parallelogram in which the cam plate moves concurrently with said handle, a toggle spring connected to said parallelogram in order to hold said handle in said neutral and two controlling positions, means supporting said wringer roll frame for movement in either direction from a normal operative position, yielding means holding said frame in said normal operative position, and a cam member operated by said frame in moving from said normal operative position engaging and operating said cam plate to shift said parallelogram and thereby the connected handle from either of said two controlling positions to the neutral position.

3. In a wringer, a wringer frame, wringer rolls mounted in said frame, drive mechanism for driving said rolls, control mechanism for said drive mechanism comprising four link elements pivoted together to form a parallelogram, said control mechanism being operable to drive said rolls in opposite directions when one of said elements is moved to either of two control positions on opposite sides of a neutral position and to discontinue operation of the rolls when said one element is returned to said neutral position, a curved cam surface formed in a selected one of said link elements having a notch and two depressed ends between which are a pair of lobes, a follower riding on the cam surface, a spring biasing said follower against said cam surface and biasing said selected element and parallelogram of which it is a part to move said one element into any one of its neutral or controlling

positions depending upon the position of said selected element, and said two lobes constituting dead center positions in the movement of said follower, means supporting said wringer frame for movement from a normal operative position with respect to said parallelogram, biasing means normally holding said frame in said normal position, and a member carried by said frame for engaging said selected element of said parallelogram to shift said parallelogram and therefore said one element to its neutral position against the force of said spring as said frame moves from its normal position, thereby to discontinue the operation of said rolls.

4. In a wringer, a wringer frame, wringer rolls mounted in said frame, drive mechanism for driving said rolls, control mechanism for said drive mechanism comprising four links pivoted together to form a parallelogram, said control mechanism being operable to drive said rolls in opposite directions when one of said links is moved to either of two control positions on opposite sides of a neutral position and to discontinue operation of the rolls when said one link is returned to said neutral position, the link of said parallelogram positioned opposite said one link constituting a cam link and having a curved cam surface which has a notch and two depressed ends between which are a pair of lobes, a follower riding on said cam surface, a spring biasing said follower against said surface and biasing said cam link and parallelogram of which it is a part to move said one link to any one of said neutral or controlling positions depending on the position of said cam link, said lobes constituting dead-center points in the movement of said follower, means supporting said wringer frame for movement from a normal operating position with respect to said parallelogram, a biasing means holding said frame in said normal position, and a cam carried by said frame for engaging said cam link to shift said parallelogram and said one link so that said one link is shifted to its neutral position first against and then with the force of said spring as said frame moves from said normal position thereby to discontinue the operation of said rolls.

5. In a wringer, a wringer head, a wringer frame pivoted to said head, wringer rolls mounted in said frame, biasing means between said head and frame biasing said frame to a normal operative position, driving mechanism on said head for driving said rolls, and control means for said driving mechanism comprising a pair of vertically spaced parallel links of substantially equal length pivoted at their centers in a common vertical line and one constituting a cam element and having an elongated curved cam surface having a central downwardly extending notch and downwardly extending ends with lobes therebetween and the other constituting a control element, the latter when moved selectively to two controlling positions effecting operation of said rolls in forward and reverse directions and when moved to a neutral position substantially midway between the other two positions effecting discontinuance of the operation of said rolls, a pair of links of equal length pivotally connecting the ends of said first two mentioned links, the four links constituting a parallelogram, a follower riding on said cam surface, a spring having one end anchored at a point between said first two links and its other end anchored to said follower so as to bias it against said cam surface, the notch in said surface and

its two ends corresponding to the neutral and the two controlling positions of said control link and said follower when in said notch or in either of said two ends holding said parallelogram in the corresponding position, and the two lobes between said two ends and notch constituting over-center points for said follower, said cam element further having a pair of spaced lateral abutments, and a cam on said frame movable with it when it moves from said normal operating position to engage with one or the other of said abutments depending upon the position of said control element thereby to shift said cam element and con-

nected control element to move the latter to said neutral position to discontinue roll operation.
